CURRENT REGULATOR UNAFFECTED BY RADIATION EXPOSURE AND ACCELERATION FORCES

Edgar B. Romberg, Whittier, Calif., assignor to
North American Aviation, Inc.
Filed June 24, 1964, Ser. No. 377,622
7 Claims. (Cl. 323—1)

This invention relates to a new and improved current regulator for providing a constant current to a load.

In some applications, it is not practical to use conventional current or voltage regulators such as zener diodes or other semiconductor type regulators, because of the adverse effect of radiation exposure. Mechanical regulators are not subject to error due to radiation exposure as are semiconductor regulators, however, conventional or electromechanical regulators are subject to error due to acceleration forces.

Accordingly, an object of the invention is to provide a new and improved current source which provides a constant current yet is not subject to error due to radiation exposure.

Another object of the invention is the provision of a mechanical current regulator which will provide a constant current even with acceleration forces being applied thereto.

Still a further object of the invention is to provide a current regulator which provides a constant current even in the presence of radiation exposure and acceleration forces.

A feature of the present invention is a current regulator having two masses that are electromagnetically supported. In the presence of acceleration, the current changes effected in the two electromagnetic suspension means are in opposition. This opposing current change is utilized to provide a constant current source in the presence of acceleration.

Other objects and advantages of the invention will become more apparent by a reading of the specification taken in connection with the accompanying drawings wherein;

FIG. 1 illustrates an isometric view in cross-sections of a current regulator embodying the invention; and

FIG. 2 illustrates a schematic diagram in block form of the control circuit utilized in the embodiment illustrated in FIG. 1.

The embodiment of the invention illustrated in FIG. 1 includes a housing having a cylindrical outer wall 10. Mounted within the ends of the cylindrical wall 10 are two magnetic air gap assemblies. The magnetic air gap mounted in the upper end of wall 10 includes a cylindrically shaped member 20 secured to wall 10 and having a circularly disposed recess 21 with a rectangular cross-section. Positioned in the upper portion of the recess 21 is a field coil winding 24 shown in FIGS. 1 and 2. The recess 21 effectively divides the main body portion 20 into an outer ring shaped portion 23 and an inner cylindrical portion 22. Member 20 is magnetically conductive. The field coil winding 24 is wound so as to provide a north pole in the center cylindrical section 22 and a south pole at the lower portion of cylindrical ring 23. The direction of current flow through field coil 24 to provide this magnetic air gap between members 22 and 23 is as shown in FIG. 2.

A first mass assembly 40 is employed having a circular base plate 41. The base plate 41 is mounted for movement longitudinally of the cylindrical outer wall 10 and electrically insulated therefrom. Some suitable mount such as an elastic hinge (not shown) is employed between the inner side of wall 10 and plate 41. Extending upwardly

2

from and transverse to base plate 41 is a cylindrical voice coil support 43. Mounted on the cylindrical voice coil support 43 is voice coil 44 as shown in FIGS. 1 and 2. The winding and direction of current through voice coil 44 is indicated by arrows in FIG. 2. As shown in FIG. 1, the cylindrical voice coil support 43 together with the voice coil 44 mounted thereon are concentric with and extend upwardly through recess 21 into the circular magnetic air gap.

At the opposite end of outer cylindrical wall 10 is another air gap assembly secured to the cylindrical wall 10. This assembly includes a cylindrical body member 30 made of a magnetically conductive material. Extending downwardly through body portion 30 is a circularly disposed recess 31 which is rectangular in cross section, as shown in FIG. 1. Mounted in the lower portion of recess 31 is a second field coil 34. The recess 31 effectively divides the cylindrical body portion 30 into a cylindrically shaped center portion 32 and outer cylindrical ring portion 33. The field coil winding 34 is wound and has current flow in the direction as shown in FIG. 2 so that the upper portion of the central cylindrical portion 32 becomes a north pole whereas the upper portion of the outer ring portion 33 becomes a south pole. Consequently, a magnetic air gap is established between portion 32 and portion 33. This air gap is circular in shape as can be seen from FIG. 1.

A second mass assembly 50 includes a base plate support 51 which is circular in shape. The base plate 51 is mounted for pivotal movement on outer cylindrical wall 10 such as by an elastic cantilever pivot 52 made of bronze, copper, etc. which is secured to base plate 51 and also to the inner surface of cylindrical wall 10. Such a mounting is also suitable for mounting of the above described base plate 41 although it will be understood that other suitable mounting can be utilized. Such a mounting establishes freedom of movement of base plate 51 (as well as base plate 41) in a direction axially of cylindrical wall 10. In addition, plates 41 and 51 are electrically insulated from walls 10. Extending downwardly from the lower surface of base plate 51 is a cylindrical voice coil support member 53 which is concentric with both the circularly disposed recess 31 and the circular base plate 51. Mounted on the lower portion of voice coil support 53 is a voice coil 54 having a direction of winding and direction of current flow therethrough as shown in FIG. 2.

Connected between base plates 51 and 41 is a spring 49 which is tensioned so as to tend to bring plates 41 and 51 towards each other. Spring 49 has one end connected to the center of the lower surface of base plate 41 with the other end secured to the upper surface of base plate 51.

A pickoff assembly 60 is employed to sense movement of base plate 41 and includes a capacitive plate 61 which is suitably insulated from cylinder 10 by an insulator 62. Capacitive plate 61 is located upwardly of the base plate 41. On the opposite side of the base plate 41 is another capacitive plate 63 which is mounted on the cylindrical wall 10 and insulated therefrom by a suitable insulator 64.

Another similar capacitive pickoff sensor 70 is employed to sense movement of base plate 51. Similarly, this assembly includes a first capacitive plate 71 and a second capacitive plate 73 which are located on opposite sides of base plate 51. Plate 71 is mounted on wall 10 and electrically insulated therefrom by a suitable insulator 72. Plate 73 is also mounted on wall 10 and electrically insulated therefrom by a suitable insulator 74. The above capacitive pickoffs are well known in the art and per se form no part of the invention.

A servo loop 80 is employed which applies a current to voice coil 44 so as to maintain base plate 41 substan-

tially undeflected with respect to its environment regardless of acceleration forces being applied thereto. A servo loop 90 is employed between capacitive pickup 70 and voice coil 54 to maintain base plate 51 substantially undeflected in its environment regardless of acceleration forces. The two voice coils are supplied with current continually due to the mechanical bias applied by spring 49. The voice coils 44 and 54 are connected in parallel and are in turn connected in series with field coils 24 and 34 as well as the load 100. More specifically, the voice coils 44 and 54 are effective to apply current to the load in parallel relationship to each other. However, in the presence of acceleration in a predetermined direction, the torquing current of one voice will increase while the torquing of the other voice coil will decrease. As a result of this relationship, the current source in voice coils 44 and 54 are effective to supply a constant current to a load regardless of acceleration forces or the direction of such forces.

As shown in FIG. 2, the capacitive plates 61 and 63 are connected to opposite ends of the center tap primary of a balancing transformer 81. The output of the secondary of transformer 81 is applied to an amplifier 82. This amplifier 82 is in turn connected to a demodulator 83 which is connected to a DC power amplifier 85. Amplifier 85 is connected to terminal 45 of coil 44. An oscillator 84 is connected to demodulator 83 and also to conducting base plate 41.

Capacitive plates 71 and 73 are connected to opposite ends of a grounded center tap primary of a balancing transformer 91. The secondary of transformer 91 is applied to an amplifier 92 which has its output connected to a demodulator 93. Demodulator 93 is connected to the input of a DC power amplifier 95 which in turn is connected to one end terminal 55 of voice coil 54 as illustrated in FIG. 2. Oscillator 94 is connected to demodulator 93 as well as to conducting base plate 51.

For purposes of illustration, the B+ supply or current supply for power amplifiers 85 and 95 is illustrated separately as a current source 86. This is done to facilitate explanation of the invention, and it will be understood that all other B+'s for the demodulators, oscillator and amplifiers are to be included within the respective schematic box as illustrated.

As stated above, power amplifier 85 is connected to terminal 45 of a voice coil 44 to provide current through the voice coil as illustrated in FIG. 2. The other terminal 46 of the voice coil 44 is connected to terminal 25 of field coil 24 to provide current in the direction indicated by arrows. Another terminal 26 of field coil 24 is connected to terminal 35 of field coil 34 to provide current in the direction indicated. The other terminal 36 of field coil 34 is connected to load 100.

Power amplifier 95 is connected to terminal 55 of voice coil 54 to provide current in the direction as indicated in FIG. 2. The other terminal 56 of voice coil 54 is connected to terminal 46 and terminals 25 of voice coil 44 and field coil 24 respectively.

In the absence of external acceleration forces, the spring 49 will effect, through servos 80 and 90, equal servo current in voice coils 44 and 54. Since these voice coils are connected in parallel electrical configuration, the sum of these two currents will be the current through field coils 24 and 34 as well as through load 100. In the presence of acceleration, the current in one of the two voice coils will increase while the current in the other voice coil will decrease so as to provide a sum current substantially equal to the sum current when no acceleration is present.

The servos 80 and 90 per se are in principal conventional torquing servos to maintain base plates 41 and 51 substantially undeflected in their environment. More specifically, these servos maintain base plate 41 equidistant between capacitive plates 61 and 63 whereas torquing

servo 90 maintains base plate 91 equidistant between capacitive plate 71 and 73.

Oscillator 84 as stated above is connected effectively between base plate 41 as shown in FIG. 2, and the center tap of the primary of transformer 81. The primary of this transformer together with the capacitance between plate 61 and base plate 41 and the capacitance between capacitive plate 63 and base plate 41 form a bridge. When base plate 41 tends to move in presence of acceleration forces, this bridge will tend to unbalance so as to provide a signal to amplifier 82 and thence demodulator 83. The oscillator 84 is applied to demodulator 83 as a reference to determine phase and amplitude of necessary torque current. The output of demodulator 83 is applied to a DC power amplifier having a current source 86, which feeds the voice coil 44. As in the conventional type servo, an acceleration or forces in one direction or the other on the base plate 41 will result in a torquing current being applied to voice coil 44 from power amplifier 85. This torquing current will maintain the base plate 41 equidistant from plates 61 and 63, and hence substantially undeflected with respect to its environment.

The servo 90 is identical to servo 80 with capacitive plate 71 and 73 being connected to opposite ends of the center tap primary of balancing transformer 91. The secondary of transformer 91 is applied to amplifier 92 whose output is connected to demodulator 93. Demodulator 93 is connected to DC power amplifier 95 so as to apply a current in the direction indicated to voice coil 54. Oscillator 94 is electrically connected to base plate 51 as well as demodulator 93. When a force or acceleration is applied to base plate 51, a torquing current will result which is applied to voice coil 54 as a restoring force on base plate 51. The operation of this servo 90 is similar to servo 80 with the bridge including the primary of transformer 91 together with the capacitance between plates 71 and 51 and the capacitance between plates 73 and base plate 51.

As stated above, the spring 49 tends to move base plates 41 and 51 towards each other. This results in an equal torquing current in voice coils 44 and 54. Since coils 44 and 54 are connected in parallel, the sum of these two currents thence is the current flowing through field coils 24 and 34 as well as load 100. Effectively, the current source is the B+ or collector current source 86 of power amplifier 85 and 95. There will be understood that a single current source is shown although obviously more than one can be utilized at a period.

If an acceleration or force tends to move base plates 41 and 51 upwardly, the servo 80 will decrease the current in voice coil 44 whereas the servo 90 will increase the current in voice coil 54. If an acceleration tends to move plate 41 and 51 downwardly, servo 90 will decrease the current in voice coil 54 whereas servo 80 will increase the current in voice coil 44. Since coils 44 and 54 are connected in parallel, a relatively constant current will be applied to field coils 24 and 34 as well as load 100 through voice coils 34 and 54 with or without the presence of acceleration. Hence, a relatively constant current is applied to maintain a relatively constant strength magnetic air gap so as to aid in maintaining a constant current to load 100.

It will be understood that when a conventional B+ current supply is employed as current source 86, the current flow through coils 24, 34, 44 and 54 will always be in the direction as shown by the arrows on these coils in FIG. 2. Hence, the spring 49 must preferably be strong enough to overcome forces of acceleration so as to continually maintain such unipolar current in both coils 44 and 54. Otherwise, the current regulation would deteriorate.

The voice coils 44 and 54 should create the same magnetic force for a given current. To achieve this, the voice coils 44 and 54 of the embodiment illustrated are identical except for the direction of winding as shown in

FIG. 2. Likewise, the field coils 24 and 34 are identical except for the direction of winding also shown in FIG. 2, so as to create the same or equal magnetic fields with the same or equal current.

If F_s is the spring force, F_a is force of external acceleration then;

$$F_s = i_1(i_1 + i_2) + F_a$$

$$F_s = i_2(i_1 + i_2) - F_s$$

where i_1 and i_2 are the current in voice coils 44 and 54, respectively. Therefore

$$2F_s = (i_1 + i_2)(i_1 + i_2)$$

This spring force is a constant. Thus, it can be seen that the sum of the currents in voice coils 44 and 54 is constant despite the presence of acceleration. Also, it will be understood that the spring constant of 49 will determine the total current.

Although this invention has been described and illustrated in detail, it is to be clearly understood that the same is by way of illustration and example only and is not to be taken by way of limitation, the spirit the scope of this invention being limited only by the terms of the appended claims.

I claim:

1. A current regulator comprising a first mass mounted for freedom of movement normal to a predetermined plane, a second mass mounted for freedom of movement normal to said predetermined plane, a first electromagnetic suspension means suspending said first mass, second electromagnetic suspension means suspending said second mass, spring means tending to move said first mass in a predetermined direction and said second mass in an opposite direction and a source of current connected in series with said first and said second electromagnetic suspension means.

2. A current regulator comprising a first mass mounted for freedom of movement along an axis normal to a predetermined plane, a second mass mounted for freedom of movement along an axis normal to said predetermined plane, a first means including a first voice coil electromagnetically suspending said first mass, second means including a second voice coil electromagnetically suspending said second mass, servo means energizing said first and said second voice coils to maintain said first and said second mass substantially undeflected with respect to its environment, spring means tending to move said first mass in a predetermined direction, and said second mass in an opposite direction and a source of current connected in series with said first and said second voice coils.

3. A current regulator comprising a first mass mounted for freedom of movement in a direction normal to a predetermined plane, a second mass mounted for freedom of movement in a direction normal to said predetermined plane, a first electromagnetic suspension means including a first air gap, a first voice coil mounted on said mass and positioned in said air gap, second electromagnetic means including a second air gap and a voice coil connected to said second mass and positioned in said second air gap, a first servo means energizing said first voice coil to maintain said first mass substantially undeflected with respect to its environment, second servo means energizing said second voice coil to maintain said second mass substantially undeflected with respect to its environment, spring means

tending to move said first mass in a predetermined direction and said second mass in an opposite direction and a source of current connected in series with said first and said second voice coils.

5. A current regulator comprising a first mass mounted for freedom of movement along an axis normal to a predetermined plane, a second mass mounted for freedom of movement along said axis, a first suspension means comprising a first air gap, a voice coil mounted on said first mass and positioned within said air gap to electromagnetically suspend said first mass, a second suspension means comprising a second air gap and a voice coil mounted on said second mass and positioned within said second air gap to electromagnetically suspend said second mass, a spring connected between said first and second masses to provide a mechanical basis thereto, a first servo means energizing said first voice coil to maintain said first mass substantially undeflected with respect to its environment, second servo means energizing said second voice coil to maintain said second mass substantially undeflected with respect to its environment, said first and said second voice coils connected in parallel a source of current connected in series with said first and said second voice coils.

5. A current regulator as set forth in claim 4 including 25 a first field coil for producing said first air gap, a second field coil for producing said second air gap, and said first and said second field coils being connected in series relationship with said first and said second voice coils.

6. A current regulator comprising a first mass mounted 30 for freedom of movement along a predetermined axis, a second mass mounted for freedom of movement along said axis, first means comprising a voice coil mounted on said first mass, a first air gap, said first voice coil mounted within said air gap to electromagnetically suspend said

35 first mass, a second air gap, a second voice coil mounted on said second mass and positioned within said second air gap to electromagnetically suspend said second mass, spring connected between said first and said second masses tending to displace said masses in opposite directions out-

40 wardly of the respective air gaps, a first servo means energizing said first voice coil to maintain said first mass substantially undeflected with respect to its environment, second servo means energizing said second voice coil to maintain said second mass substantially undeflected with

45 respect to its environment, a source of direct current, said source connected to one end of said first and said second voice coils tending to move said first and said second masses in opposite directions, said voice coils being connected in parallel circuit configuration and said parallel circuit configuration being connected in series with a load.

7. A current regulator as set forth in claim 6 including 50 a first field coil for producing said first air gap, a second field coil for producing said second air gap, in wherein said parallel circuit configuration, said first field coil, said second field coil and said load are connected in series.
